UNITED STATES PATENT OFFICE.

THORSTEN VON ZWEIGBERGK, OF CLEVELAND, OHIO, ASSIGNOR TO THE WALKER COMPANY, OF SAME PLACE.

GOVERNING, REVERSING, AND BRAKING CONTROLLER.

SPECIFICATION forming part of Letters Patent No. 611,088, dated September 20, 1898.

Application filed February 23, 1898. Serial No. 671,370. (No model.)

To all whom it may concern:

Be it known that I, THORSTEN VON ZWEIGBERGK, a subject of the King of Sweden and Norway, residing at Cleveland, in the county 5 of Cuyahoga and State of Ohio, have invented a certain new and useful Improvement in Governing, Reversing, and Braking Controllers, of which the following is a full, clear, and exact description, reference being had to the 10 accompanying drawings.

One of the objects of my invention is to provide a simple and compact controller which while requiring but two operating-handles shall have the capacity of performing the 15 three operations of governing and reversing the motors of a car and applying a brake thereto.

Another object is to combine with the controller, brake, and connections an automatic 20 switch for governing the current to the brake.

A third object is to provide simple and efficient means for cutting out either motor and the equalizing cross connection between them provided for the electric brake.

25 The invention consists of the means I employ for attaining the objects above set out and other minor objects, and it may be best described as consisting of the combinations of parts hereinafter specified, and definitely 30 enumerated in the claims.

The drawings clearly show my invention.

Figure 1 is a front elevation of the controller, the front cover being removed; and Fig. 2 is a side elevation of the same with the 35 cover in place, but a portion of it broken away. Fig. 3 is a top view of the controller; and Figs. 4, 5, and 6 are horizontal sections of the controller on lines 4 4, 5 5, 6 6, respectively, of Fig. 1. Fig. 7 is an enlarged plan 40 of the detent mechanism of the two cylinders, the position of the two operating-levers being indicated by dotted lines. In this view the governing-cylinder is at the off position and the reversing-cylinder at the reversing position. 45 Fig. 4, where the same mechanism is shown on a smaller scale, the governing-cylinder is at the off position and the reversing-cylinder at the ahead position. Fig. 8 is a diagram showing the development 50 of the two cylinders, their contact-fingers,

and the connections with the motors, resistances, electric brakes, &c.

The same letters of reference designate the same parts on all of the figures.

I will first describe the construction and 55 operation of the controller itself and then its connection with the motors, resistances, and brakes and its operation when installed.

The controller shown includes a governing and a reversing switch, each consisting of a 60 row of contact-fingers and a coöperating contact-cylinder, the term "cylinder" being used in its ordinary acceptation in the controller art and meaning a shaft and various contact-segments carried thereby through the 65 intervention of suitable insulation.

In the governing-switch, D represents the shaft of the cylinder, and d' to d^{16} , inclusive, the contact-segments, which are supported by suitable ribbed arms d , projecting from 70 hubs D' , which surround an insulating-sleeve D^2 , which itself surrounds the shaft. The arrangement of the governing-switch (which is of the series-parallel type) is such that the contact segments or plates d' to d^{11} are all 75 electrically connected together, and the contact-plates d^{12} to d^{15} are electrically connected together, while the contact-plate d^{16} is insulated from all the others and is connected with the controller-frame, which lat- 80 ter is grounded. The connection between the contact-segments referred to is preferably made by copper strips D^3 , which are embedded in proximate hubs, while insulating-collars D^4 are placed between those hubs which 85 are not in electrical contact and beyond the end hubs. The shaft D is journaled in suitable bearings $e e'$, carried by the controller-frame E, and has the usual operating lever or handle D^5 .

90 Suitably insulated and supported are a series of contact-fingers u' to u^{16} , adapted to engage with the contact-plates of the governing-cylinder. These contact-fingers are connected with resistances and with the motors in 95 the usual manner, so that the lever D^6 by turning the cylinder into successive positions connects the motors in series with themselves and with a number of resistances and then successively cuts out these resistances, then 100

connects the motors in parallel through resistances, and then cuts out these resistances, leaving in its final position the motor in parallel without resistance.

- 5 H represents the shaft of the reversing and braking cylinder. This cylinder is built of segments h' to h^{21} , inclusive, disposed and connected as hereinafter explained. These segments are carried in the usual manner by 10 suitable arms h , extending from hubs H' , which are separated by insulating-collars H^1 and surround an insulated sleeve H^2 , which itself surrounds the shaft H. This shaft is journaled in suitable bearings e^2 and e^3 , carried by the controller-frame, and is independent 15 of the shaft J of the reversing-lever j , hereinafter referred to, and is adapted to be turned on its axis without regard to that lever. The shaft H carries at its upper end the 20 detent-wheel or, as it is usually called, "indicator-wheel" K, rigidly secured to it, and has notches with which a spring-pressed roller g' is adapted to engage. The hub k of this indicator-wheel projects above the shaft H, so 25 as to leave a central recess, and in this recess loosely stands the shaft J, with which the reversing-lever j engages. This shaft J is also journaled in a suitable bearing e^4 , carried by the frame.
- 30 Between the bearing e^4 and the hub k is a sleeve M, loose on the shaft J, but compelled to rotate with it by a spline j' on the shaft taking into a longitudinal groove n in the sleeve. On the under side of this sleeve is a 35 projection n' , adapted when the sleeve is in its lowest position to engage with a correspondingly-shaped notch k' in hub k . On the upper side of the sleeve N is a projection n^2 , which is adapted when the sleeve is elevated 40 to engage with either of a pair of notches e^5 and e^6 on the under side of the bearing e^4 . From this construction it follows that if the sleeve N is in its lowest position the shaft J, and hence the reversing-lever j , is in rigid 45 engagement with the shaft H and capable of operating the reversing-cylinder, whereas if the sleeve N is elevated the shaft J and the operating-lever j are not only disengaged from the shaft H, but are locked in place by the 50 projection n^2 engaging with one of the notches in the stationary bearing e^4 .

Surrounding the sleeve N is an annular groove n^3 , into which take pins p , projecting inward from a yoke or lever P, which is pivoted on a horizontal pivot to lugs projecting from the frame. This lever is therefore adapted to shift the sleeve along the shaft J. Surrounding the shaft D of the governing controller above its detent-wheel L is a cam 60 in the form of a collar O, having projecting rims o' o^2 , which at a certain point incline downward, as at o^3 , and thus leave between them a cam-groove o . The downward bend o^3 in this cam-groove is on the side which is 65 next to the lever P when the lever D^5 is at its off position. Into this groove projects a roller p' , carried by the lever P. This roller

being in the depression o^3 of the cam-groove when the operating-handle D^5 is at the off position then holds the lever P in its lowest position, which is when the sleeve N is in engagement with the hub of the detent-wheel K on the shaft H. When, however, the operating-lever D^5 is turned in either direction from the off position, the roller p' is elevated 70 by the higher portion of the groove o coming beneath it, and this elevates the sleeve N into engagement with one of the notches in the bearing e^4 , thus releasing the shaft H and locking the shaft J and the lever j . 80

From the description just given it will be apparent that whenever the lever D^5 is at working position—that is, when there is any current on—the lever j is necessarily disconnected from the reversing-cylinder and 85 locked in position. It is therefore not only impossible to reverse the motors while the current is on, but it is impossible to displace the reversing-lever. If desired, the rim o' of the cam O may be omitted and a spring acting downward on the lever P substituted therefor. When the governing-lever is at the off position, if the reversing-lever is turned to its off position, which is between the ahead and the reverse positions, the projection n^2 will come under the bearing e^4 between the notches e^5 and e^6 . This prevents the elevation of the sleeve when in this position, and the sleeve holds the lever P and its roller p' in stationary position, and this roller prevents the rotation of the collar O and thereby locks the governing-cylinder against movement. The lever j is removable only in its off position, and preferably the lever D^5 also, as is customary; but, as shown, when the lever j is at its off position the lever D^5 cannot be turned even if left on, and thus if the motorman is obliged to leave his car he may simply set the reversing-lever at the off position, and he can then take off this lever, 110 which is much smaller than the lever D^5 , and put it in his pocket.

The construction and operation thus far described are not claimed in this application, but in another application filed by me April 115 29, 1898, Serial No. 679,195.

In order that the controller may be able to govern and reverse the motors and apply the electric brake with simply its two cylinders and without the necessity of lengthening the 120 shaft of the governing-cylinder and putting on several contact-segments below those required for the governing operations, I add to the reversing-cylinder (on either side of the reverse position) contact-plates adapted to 125 reverse the electric brake, I provide electric-brake positions for the governing-cylinder, which are back of the off position, and I supply a suitable connection between the two cylinders, so that when the operating-lever D^5 is turned to one of these electric-brake positions the reversing-cylinder (from which the shaft J and lever j are disconnected) is turned thereby either into the position of elec- 130

tric-brake ahead or electric-brake reverse, according as the reversing-lever left it at the ahead or the reverse position.

I will now describe in detail the connection 5 between the two cylinders above referred to and its operation.

Referring more particularly to Figs. 4 and 7, where the detent-wheels L and K are shown in plan, it will be seen that the rollers q and 10 q' , which engage with the notches of these detent-wheels, are carried by independent arms Q and Q', which for simplicity of construction are pivoted on one pivot at q^2 and are forced into position by one spring q^3 , surrounding 15 the studs q^4 , which project toward each other from lugs q^5 on the backs of arms Q and Q'. If the lever D^5 is revolved to the right, it turns the governing-cylinder through four series positions and three parallel positions until its 20 movement is stopped by the projection l of the indicator-wheel engaging with the roller q . This movement is totally independent of the reversing-cylinder. When the lever D^5 is brought back to the off position, the reversing-lever j is released and thrown into engagement with the reversing-cylinder, and the latter may be turned to reverse the motors by means of that lever. Between the ahead and reverse positions of this reverse-lever is 25 the off position at which it may stop, if desired, and at which it locks the lever D^5 , as stated. In the indicator-wheel K, on the side next to the indicator-wheel L, are a pair of notches k^2 and k^3 . These notches are in such 30 position that one or the other of them is engaged by the projection l of the indicator-wheel L when the latter is moved from the off position to the first electric-brake position. Thus if, as shown in Fig. 7, the reversing-lever 35 has left the indicator-wheel K in the reverse position (the car thus moving backward) the projection l engages with the notch k^2 , and before the lever D^5 has come into the first electric-brake position the indicator-wheel K is turned to the right a distance 40 sufficient to bring it into the electric-brake reverse position—that is, the last indicator-notch k^8 comes into engagement with the roller and the last row of contact-segments 45 h^{10} to h^{21} into engagement with the contact-fingers. This leaves the electric brake so connected up that it is applied through two resistances. These resistances are cut out as 50 the lever D^5 is moved to the second and third electric-brake positions. When the lever D^5 is brought back to the off position, it brings back the indicator-wheel K and the cylinder secured thereto to its former position. If in 55 this position the reversing-lever is set at the ahead position, the notch k^3 is brought into the position formerly occupied by the notch k^2 , and if now the lever D^5 is turned to the electric-brake position the projection l engages with the notch k^3 and swings the reversing-cylinder into the position of electric-brake ahead, which is the position where the 60 third indicator-notch k^6 engages with the

roller q' . It will thus be seen that if the reversing-lever leaves the reversing-cylinder at the ahead position that cylinder is in position to be turned into the electric-brake ahead position by the movement of the lever D^5 to the electric-brake position, while if the reversing-lever leaves its cylinder at the reverse position that cylinder will be turned to the electric-brake reverse position by the same movement of the lever D^5 . Therefore in ordinary running the lever D^5 is the only one that need be handled, its forward movement governing the motors and its rearward movement the electric brake, and when the car is to be reversed the one reversing movement of the lever j leaves the lever D^5 in position to perform the same operations for the rearward movement of the car. 85

The operation of the controller for the series and parallel positions and of the reversing-switch for the ahead and reverse positions will be readily understood by those skilled in the art from Fig. 8, where the controller is represented as connected with two motors and the resistance R, which may be in the circuit in its entirety (r') or only as to its portion r^2 or its portion r^3 . $R' R^2 R^3 R^4$ represent the conductors leading to this resistance. $A' A A' A^2 A A^2$ and $F' F F' F^2 F F^2$ represent the conductors to and from the respective armatures and fields of the motors. T represents the conductor from the trolley, and S that to the automatic switch for the electric brake. The contact-fingers for the governing cylinder are represented by u' to u^{10} , inclusive, and those for the reversing and braking-cylinder by v' to v^9 , inclusive. Of the latter the fingers v' , v^5 , and v^9 are adapted to be held out of the path of their corresponding segments, thus cutting out the lines they represent, as hereinafter explained. C' represents a conductor leading from contact-fingers u' and u^7 to contact-finger v' , and C^2 represents a conductor leading from contact-finger u^8 to contact-finger v^9 . 90 95 100 105 110 115

I will now describe the course of the current for a few positions of the controller, as illustrative. When the governing-cylinder 115 is in position No. 1 series and the reversing-cylinders in position ahead, the current comes from the trolley via T to contact-finger u^5 , to contact-plate d^{10} , to contact-plate d^9 , to contact-finger u^4 , through the total resistance r' 120 to conductor C' , to contact-finger v' , to contact-plate h' , to contact-plate h^3 , to contact-finger v^3 , through the armature of motor No. 1 to contact-finger v^2 , to plates $h^2 h^4$, to contact-finger v^4 , through the field of motor No. 125 1 to contact-finger u^{10} , to contact-plates d^{15} d^{13} , to contact-finger u^8 , conductor C^2 , to contact-finger v^9 , to contact-finger v^5 , through the armature of motor No. 2 to contact-finger v^8 , to contact-finger v^6 , and through the field 130 of motor No. 2 to the ground. The positions 2, 3, and 4 cut out portions and then the whole of the resistance R, while the reverse position of the reversing-cylinder reverses the di-

rection of the motors. In position No. 5 the current passes from the trolley to contact-finger v^5 , plate d^{10} , plate d^7 , contact-finger u^3 , through the portion r^2 of the resistance, and, 5 dividing, partly to the conductor C' and partly to the contact-finger u^7 , plates d^{12} and d^{14} , contact-finger u^8 , and the conductor C^2 . The current thus comes to the plates v' and v^9 of the reversing-switch and passes through the 10 motors in parallel, coming out via the conductor FF^2 to the ground and via the conductor F' to the plate d^{16} to the ground. Parallel position 6 leaves only the portion r^3 of the resistance in circuit, and portion 7 cuts 15 out the whole of it.

I will now describe the connection and operation of the brake.

In the diagram Fig. 8 I have indicated at 20 $B' B^2$ brake-shoes for each axle of the motor-car, and $B^3 B^4 B^5 B^6$ indicate similar shoes to two trail-cars. This brake operates in the usual manner of an electric brake—that is, by the current generated by the movement of the motor-armature flowing through field-coils carried by the brake-shoe, which find 25 an armature in a disk secured to the axle, and hence retard or stop that disk and the axle. Thus in turning on the electric brake the electric-brake terminal (indicated at S) is 30 substituted for the trolley-terminal, and the current is reversed by the reversing-cylinder.

The electric-brake portion of the governing-switch shown is such as to connect the motors in parallel, though, if desired, they might be 35 connected in series. If they are connected in parallel, it is necessary that there be a cross connection between their fields when they are braking to equalize their currents and prevent the greater current generated by 40 one motor from flowing back and counteracting the current from the other motor. This cross connection, however, is only desirable when the motors are operating as generators for the electric brake. I therefore establish 45 the cross connection at the reversing-cylinder and by means of the contact-segment h^{17} , connected with the segment h^{18} and the portion h^{22} of the segment h^{11} , (said segments adapted to engage with the field-terminal of motor No. 50 2,) and the contact-finger v^5 , which is connected with the field of motor No. 1, but is adapted to be cut out, as hereinafter explained. When this finger v^5 is not cut out, there is in each of the electric-brake positions, 55 therefore, a cross connection from F^2 through h^{18} and h^{17} or through h^{11} and h^{22} to v^5 to FF' .

Should a motor burn out, it is not only necessary that it should be cut out, but that the equalizing cross connection between the two 60 motors be cut out, so as to prevent the grounding of the brake-current when the reversing-switch is at the brake position. I accomplish this by endowing the contact-fingers v' , v^9 , and v^5 , which are part of the connection from 65 the governing-cylinder and of the cross connection between the motors, with the capacity of being withdrawn entirely from the path of

the reversing-cylinder, and I provide hooks V , adapted to take over pins v , projecting from these fingers, and thus retain them in this withdrawn position. If motor No. 1 should burn out, the motorman opens his controller-case and withdraws the contact-fingers v' v^5 and hooks them back out of the way, while if motor No. 2 is disabled he withdraws the fingers v^9 v^5 . In either case he runs his car on the parallel positions 5, 6, or 7 of the controller. In Fig. 8 the hollow squares at the right of the contact-fingers v' v^5 v^9 illustrate the withdrawn position of those fingers. 75 8c

I do not claim in this application, broadly, either the method of cutting out a motor by withdrawing a contact-finger or the mechanism incident thereto, as such are shown and claimed in applications, Serial Nos. 671,289 85 and 679,194, which I filed February 23, 1898, and April 29, 1898, respectively. I do claim herein, however, the combination of parts by which I can cut out one of a plurality of motors and also a cross connection between them 90 when the parts are at electric-braking positions.

In order to automatically govern the electric brake, I provide between the terminal S and the brake an automatic switch S' , capable of 95 increasing the resistance to the brake-current when the latter rises too high either from the operator's cutting out resistance too quickly or from the too-rapid revolution of the motor-armatures. This switch consists of a magnet 100 s in circuit with the brake through a resistance and one or more armatures adapted to short-circuit a whole or a portion of the resistance. In the form shown in the drawings there are two armatures, and three paths in 105 parallel are thus provided for the current, the first and least resisting being via the conductor s' to the armature s^2 , to the conductor s^3 , and the magnet, the second being through a portion of the resistance s^5 to the conductor 110 s^6 , the armature s^7 to the magnet, and the third being through the whole resistance s^8 to the magnet. When the current first flows, it passes mostly along the first of these paths. As the current increases in strength the magnet 115 draws the armature s^2 away from its contact-point and leaves the current flowing mostly through the second path. If the current's strength increases still more, the second path is opened and the current flows 120 through the whole resistance s^5 . The spring s^4 , resisting the movement of the armature s^2 , is weaker than the spring s^8 , which resists the movement of the armature s^7 , which results in the first-mentioned path being opened first. 125 As the force of the current dies down the resistance is short-circuited by the armatures coming back to their original positions. 130

Inasmuch as the current generated by the motors when the brake is thrown on builds up very rapidly, owing to the initial rapid rotation of the armatures, then falls as the braking action begins to decrease the speed, and rises as the governing resistance is cut out,

and again falls, it will be seen that such an automatic switch is very desirable for preventing the current rising too high on the one hand and for preventing it being wasted in 5 overcoming useless resistance on the other.

When there is no trail-car, the current passes from the brake on the motor-car direct to the ground. In order to provide for the application of electric brakes on the trailer, however, I provide between each brake and the ground connection a spring-jack W. This jack has two terminals w w' normally in contact with each other, and thus when there is no car following closing the circuit from the 10 brake to the ground. When, however, a trailer is attached, a plug W', having a terminal w^2 and a proximate bar of insulation w^3 , is inserted between the springs w and w' . The spring w^2 is connected with the electric 15 brake on the trailer, and it thus carries the current from the electric brake on the motor-car to that on the trailer, while the insulating-brake w^3 holds the spring w' out of action. The current thus goes to the ground from the 20 trailer. If a second trailer is used, it is plugged into the first trailer's ground connection in a similar manner. Thus the electric brakes, no matter how many are used, are all in series, the current going to the ground from the last 25 trailer. If a second trailer is used, it is plugged into the first trailer's ground connection in a similar manner. Thus the electric brakes, no matter how many are used, are all in series, the current going to the ground from the last 30 one.

Having described my invention, I claim—

1. The combination, with a pair of motors and a controller, of a reversing-switch having contact-fingers and contact-plates adapted to 35 connect the motors in one direction or in the reverse direction and having a contact-finger connected with the field of one motor and a contact-plate adapted to connect that finger with the field of the other motor, whereby a 40 cross connection between the fields of the motors is adapted to be established by the movement of the reversing-switch, substantially as described.

2. The combination, with a pair of motors, 45 and an electric brake, of a reversing-switch adapted to stand in four positions and having contact-fingers and suitable connections between the fingers and motors whereby when the switch is in the first position the motors 50 are connected in one direction, when the switch is in the next position the motors are reversed and a cross connection established between their fields, when the switch is in the third position the motors are reversed without such cross connection, and when the 55 switch is in the fourth position they are connected as originally except they have such cross connection, substantially as described.

3. In a controller, in combination, a switch, 60 adapted to apply an electric brake, a reversing-switch having positions for the motor and for the electric brake, a lever adapted to move the reversing-switch from the motor ahead position to the motor reverse position, and vice versa, and connecting mechanism 65 between the applying-switch and the reversing-switch, one member of said mechanism

being rigid with the reversing-switch, said member having two engageable parts with one of which a member moved by the applying-switch must engage when that switch moves from the off to the electric-brake position, and vice versa, but the position in which the reversing-lever has left the reversing-switch determining with which one of said two engageable parts the other member engages, substantially as described. 70

4. The combination, in a controller, of a governing-cylinder, a reversing-cylinder, a plate secured to the shaft of the reversing-cylinder, an arm carried by the governing-cylinder and adapted to engage a shoulder on said plate when the governing-cylinder is turned to an electric-brake position if the reversing-switch is in the ahead position, and 80 adapted to engage another shoulder on said plate when the governing-cylinder is so turned if the reversing-cylinder is in the reverse position, the movement of the governing-cylinder in either event swinging the reversing-cylinder to the corresponding electric-brake position, substantially as described. 85

5. The combination, in a controller, of a governing-cylinder, a reversing-cylinder, an operating-handle for the latter, a plate or 90 other arm rigid with the shaft of the reversing-cylinder, an arm moved by the governing-cylinder and adapted to engage with said plate when the governing-cylinder moves from off to the electric-brake position in either of two 95 positions according as the reversing-lever has left the reversing-switch in its ahead position or its reverse position, said two engageable positions of said plate being substantially the same angular distance apart as the ahead and 100 reverse positions of the reversing-switch, 105 substantially as described.

6. The combination, in a controller, of a governing-cylinder, a reversing-cylinder, a projection carried by the governing-cylinder, 110 a plate having two notches carried by the reversing-cylinder, one of said notches being adapted to be engaged by said projection when the governing-cylinder is turned to an electric-brake position if the reversing-cylinder is in its ahead position, and the other of 115 said notches being adapted to be engaged by said projection when the governing-cylinder is so turned if the reversing-cylinder is in the reverse position, the movement of said projection, in either event, swinging the reversing-cylinder to the corresponding electric-brake position, substantially as described. 120

7. The combination, in a controller, of a governing-cylinder adapted to move in one 125 direction from its off position to govern motors, and in the other direction to apply an electric brake, a reversing-cylinder having positions for the motors ahead or reversed and for the electric-brake ahead or reversed, 130 a notched indicator wheel or plate for each cylinder, a spring-pressed roller or detent for each cylinder adapted to take into said notches, the indicator-wheel of the governing-

cylinder having a projection l which comes between the last electric-brake position and the last parallel position, and by impinging on one side or the other against the roller for that indicator-wheel forms a stop for the governing-controller in either direction, and the indicator-wheel of the reversing-switch having a pair of notches k^2 k^3 distinct from those used by the spring-pressed roller for that 5
10 wheel and occupying such position that the projection l , when the governing-switch moves from the off to the first electric-brake position, will engage with the notch k^2 if the governing-switch is in the reverse position, or 15 with the notch k^3 if the governing-switch is in the ahead position, and in either case will move the reversing-switch to set it at an electric-brake position for that direction of car movement for which the reversing-switch was 20 set before the governing-switch moved to apply the brake, substantially as described.

8. The combination, with a pair of motors and an electric brake, of a cross connection between the two motors, said cross connection 25 being by means of a contact-finger and a contact-plate which are brought into engagement at an electric-braking position of a controller and a cut-out for each motor and for the cross connection which may be operated independently of the position of the controller which establishes the cross connection, whereby when either motor burns out its cut-out and the cut-out of the cross connection may be opened and the electric brake operated by 30 the other motor, substantially as described. 35

9. The combination, with a pair of motors and an electric brake, of a cross connection between the two motors, said cross connection being by means of a contact-finger and a contact-plate of a controller which are brought into engagement at an electric-braking position, said contact-finger being adapted when the controller is at an electric-brake position to stand withdrawn from the path of the surface of the contact-plate with which it normally contacts in such position, and mechanism for retaining the contact-finger in this withdrawn position whereby the cross connection may be cut out whenever a motor is 40 45

cut out and thus the remaining motor used 50 to operate the electric brake, substantially as described.

10. The combination with an electric brake, of a controller adapted to apply the brake and govern it by cutting out resistance, and 55 an automatic switch included in the circuit between the controller and the brake and short-circuiting a resistance at the time the brake is applied, but adapted to open that short circuit when the current strength increases to a desired amount, substantially as described.

11. The combination with an electric brake and a controller adapted to apply the brake, of an automatic switch inserted in the circuit 60 to the electric brake, and adapted to increase the resistance to the current in that circuit as the strength of the current increases, substantially as described.

12. The combination with a motor, an electric brake, and a resistance, of a controller adapted to apply and govern the motor and brake by means of that resistance, and an automatic switch in the circuit between the controller and electric brake adapted to counteract too great an increase of the current strength caused by too rapid a revolution of the motor or too quick a cutting out of resistance by the controller, substantially as described. 70 75 80

13. The combination, with a motor, a controller and an electric brake, of an automatic switch in circuit with the electric brake, said switch comprising a magnet, armatures therefor and a resistance, said armatures when 85 drawn toward the magnet being adapted to cut out paths of less resistance than those thereafter remaining, the armature which cuts out the path of least resistance being operated by a less magnetic pull than the other, 90 substantially as described.

In testimony whereof I hereunto affix my signature in the presence of two witnesses.

THORSTEN VON ZWEIGBERGK.

Witnesses:

ALBERT H. BATES,
E. B. GILCHRIST.
